[57] **CLAIM**

The ornamental design for a loft bed system, as shown and described.

DESCRIPTION

FIG. 1 is a perspective front view of the loft bed system design;

FIG. 2 is a right side elevational view of the loft bed system, the left side elevational view being a minor image of FIG. 2;

FIG. 3 is a front elevational view of the loft bed system;

FIG. 4 is a rear elevational view of the loft bed system;

FIG. 5 is a top plan view of the loft bed system;

FIG. 6 is a rear view of the desk and shelf unit of the left bed system of FIG. 1; and,

FIG. 7 is a detailed perspective view of the connection between one corner of the bed springs and the associated vertical support member.

The broken lines are for environmental purposes and form no part of the claimed design.
